(57) **CLAIM**

The ornamental design for the shield for helmet, as shown and described.

DESCRIPTION

FIG. 1 is a top, front and left side perspective view of a shield for helmet showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a transverse cross-sectional view at 8—8 of FIG. 6; and,

FIG. 9 is a left side elevational view of the shield for helmet shown attached to a helmet.

The broken line showing of a helmet in FIG. 9 is for illustrative purposes only and forms no part of the claimed design.
